MACHINE FOR COILING AND PACKAGING
STRAND MATERIAL

Michael J. Dempsey and Frederick W. Reher,
Waterbury, Conn., assignors to The Chase
Companies, Incorporated, Waterbury, Conn., a
corporation

Application March 13, 1933, Serial No. 660,448

4 Claims. (Cl. 242—82)

This invention relates to an improvement in machines for coiling or packaging strand material, and relates in particular to such machines primarily designed for coiling or packaging wire, though not so limited.

Wire, as ordinarily coiled or packaged, is either wound upon reels or spools, or loosely coiled in bundles, much in the manner in which rope is coiled by seamen. This latter type of coiling may be aptly termed "loose-coiling" in contradistinction to the mode of coiling in which the coils are helically or spirally wound uniformly and tightly against each other.

The present invention relates in particular to machines for loose-coiling strands and is especially adapted for loose-coiling soft metal wire or the like, as will appear from the following.

Many different types of machines and apparatus have heretofore been devised in efforts to provide suitable means for the loose-coiling of wire, etc., but for various reasons, among which may be mentioned tangling of the coils, kinking and stretching of the strands, etc., the results have been more or less indifferent and faulty.

One of the objects of the present invention is to provide a superior machine for loose-coiling strand material.

Another object is to provide a machine and method of the class described by means of which strands may be readily and conveniently loose-coiled without tangling the coils or stretching or kinking the strands.

A further object of the present invention is to provide a reliable and effective machine for coiling or packaging strand material by means of which strands of soft material, such as annealed brass wire, may be loose-coiled without harmful distortion.

Other objects and advantages will appear to those skilled in the art from the following, taken in conjunction with the accompanying drawings and the appended claims.

The present invention is the result of long and varied experiments, by means of which it has been discovered that by providing a coil-receiver mounted for rotation about an upstanding axis and adapted to receive strands from above, in combination with strand-feeding means positioned above the said receiver, and rotating the said strand-receiver at a predetermined ratio of speed with respect to the speed of the said strand-feeding means, wire or other strand material, even though of low tensile strength, may be readily loose-coiled or packaged with the minimum of stretching, distortion, kinking or snarl-

ing, all as will more fully appear from the following.

In the accompanying drawings:

Fig. 1 is a view mainly in side elevation and partly in vertical section of one form which a strand-coiling machine embodying our invention may assume;

Fig. 2 is a top or plan view thereof;

Fig. 3 is a broken transverse sectional view taken on the line 3—3 of Fig. 1 but also showing the outer guard-member of the strand-receiver in vertical central section;

Fig. 4 is a broken transverse sectional view taken on the line 4—4 of Fig. 1;

Fig. 5 is a broken detail sectional view of the strand-feeding member and a portion of the inner guard-member of the strand-receiver, on a larger scale;

Fig. 6 is a horizontal sectional view taken on the line 6—6 of Fig. 1 but on a larger scale;

Fig. 7 is a broken vertical central sectional view taken on the line 7—7 of Fig. 1, but on a larger scale;

Fig. 8 is a transverse sectional view taken on the line 8—8 of Fig. 7;

Fig. 9 is a view partly in side elevation and partly in vertical central section of a modified form of combined strand-receiver and strand-feeder constructed in accordance with this invention; and

Fig. 10 is a corresponding view of another form of strand-receiver useful in connection with the present invention.

The particular strand-coiling machine herein chosen for the illustration of the present invention includes as shown a rotatable strand-feeding drum or head 20 pinned to the lower end of a vertical drive-shaft 21 depending from a gear-box 22 containing a reduction gear system not shown in detail but interposed between the drive-shaft 21 and the shaft 23 of an electric motor 24 to transmit the power of the said motor, at reduced speed, to the said head. The motor 24 and associated parts are mounted upon the upper surface of a platform 25 supported by a cylindrical standard or column 26 upstanding from an integral base-plate 27.

The strand-feeding drum 20 before referred to is preferably formed with a crowned periphery 28 in which is formed a shallow semi-circular annular groove 29 in which the wire or other strand material 30 to be loose-coiled is held by an endless belt or strap-like holder 31 which snugly embraces slightly more than half of the periphery of the said drum, as clearly shown in Fig. 6. The

belt 31, in addition to engaging the periphery of the drum 20, passes over four grooved idler-pulleys 32, 33, 34 and 35, each of which is rotatably mounted upon the under face of the platform 25.

5 The upper edge of the strand-feeding drum or head 20 is preferably provided with an annular laterally-projecting flange 36 and at its under side is provided with a depending locating-flange 37 fitting within a cylindrical inner guard-member 38 formed of sheet-metal and preferably forming a feature of a ring-like strand-receiver 39 preferably having an outer cylindrical guard-member 40 of sheet material spaced from the inner guard-member 38 to provide a ring-like chamber 41 for the reception of the strand material as the same is coiled in a manner as will hereinafter appear. The upper edge of the outer guard-member 40 is preferably outwardly flared as at 42 and is preferably spaced from the inner guard-member to such a degree as to be substantially as much larger than the diameter of the drum 20, as the inner guard-member is smaller than the same. By way of illustration of the preferred proportioning of the parts, let it be presumed that 25 the drum 20 is of 14-inch diameter, in which case the outside diameter of the inner guard-member 38 might be approximately 12 inches, in which case the internal diameter of the outer guard-member 40 would preferably be 16 inches.

30 The strand-feeding drum 20 is also provided with an integral depending clutch-member 43 normally engaged with a complementary clutch-member 44 secured to the upper end of an upstanding shaft 45 coaxially arranged with respect 35 to the drive-shaft 21 and having its upper end slightly tapered, as shown, for ready entry into an axial socket 46 formed in the clutch-member 43. The clutch-member 44 is preferably provided, as shown, with an annular centering-flange 47 which fits freely within a central perforation 48 formed in a webbing 49 inwardly projecting from the inner guard-member 38 and serves to prevent undue tilting of the guard-member 38.

45 Adjacent its lower end the upstanding shaft 45 has keyed to it a rotary table 50 having a series of steps 51 on its upper surface for the reception respectively of various-sized coil-receivers. The extreme lower end of the shaft 45 bears in a suitably-bushed vertical bearing-passage in 50 the end of a carrier-arm 52, between the upper face of which latter and the under face of the table 50 is positioned an antifriction thrust-bearing 53, as clearly shown in Fig. 4 of the drawings.

55 The carrier-arm 52 just above referred to radially offsets from a band-like rotary carrier generally designated by the numeral 54 and also carrying a radially-offsetting arm 52^a corresponding to but located diametrically opposite the arm 52 just described. The rotary carrier 54 is, as 60 stated, of ring-like form and is diametrically split, as shown in Fig. 8, to facilitate its entrance into an annular groove 55 formed in the periphery of a vertically-reciprocating supporting-ring generally designated by the numeral 56. The sections of the rotary carrier 54 are each formed with outwardly-projecting ribs 57 through which suitable bolts 58 extend for uniting the parts into a unitary structure.

70 The supporting-ring 56 is also diametrically split as shown and the respective parts are each formed with offsetting ears 59 through which suitable bolts 60 pass for uniting the parts. As clearly shown in Fig. 8, the supporting-ring 56 is formed internally at diametrically-opposite 75 points respectively with vertical guide-grooves 60,

each of which engages and rides upon a vertical track-like boss 61 formed upon the standard 26.

At diametrically-opposite points the supporting-ring 56 is also formed with a pair of inwardly-extending coupling-lugs 62—62 respectively projecting inwardly into the interior of the standard 26 through clearance-openings 63—63 therein. The respective inner ends of the coupling-lugs 62—62 are suitably notched and engaged with a cross-head 64 mounted upon the upper end of a vertically-movable supporting-rod 65 axially located within the standard 26, as shown in Fig. 7, and carrying at its lower end a piston 66 located within a cylinder 67 supported at its lower end upon a cross-pin 68 15 extending diametrically through the standard 26 adjacent the lower end thereof.

As will appear from the foregoing, the rotary carrier 54 is mounted upon the supporting-ring 56 with capacity for rotary movement with 20 respect thereto, which movement is facilitated by an annular series of ball bearings 69, while the supporting-ring 56 is mounted with capacity for vertical movement on the standard 26, so that the carrier 54 may have both rotary movement in a horizontal plane, and vertical movement for the purpose as will hereinafter appear.

The cylinder 67 is supplied with compressed air through a pipe 70 leading to a control-valve 71 which is supplied with compressed air through 30 a feed-pipe 73. The control-valve 71 may be of any approved type, but as shown it is provided with an oscillating operating-handle 74 having a depending cam 75 engageable with a roller 76 mounted in the upper end of a vertical safety- 35 plunger 77 which is mounted for reciprocation in a lug 78 offsetting from the standard 26 and is encircled by a helical spring 79 exerting a constant effort to move the said plunger upward. The lower end of the safety-plunger 77 is adapted to enter one or the other of two diametrically-opposite vertical sockets 80 formed in the upper surface of the rotary carrier 54 when the said carrier is in position to align the shaft 45 or a corresponding shaft 45^a with the drive-shaft 21, as will more fully hereinafter appear.

40 It may be here stated that the arm 52^a of the rotary carrier 54 is of the same character as the arm 52 and, like the same, carries a rotary table 50^a, an upstanding shaft 45^a, and a clutch-member 44^a, etc., and is adapted to mount, with capacity for rotation, a strand-receiver similar to the strand-receiver 39 shown as mounted upon the table 50. When occasion requires, the carrier may be rotated to align the shaft 45^a with the shaft 21, as will later appear.

45 For the purpose of leading the wire or other strand-material 30 to the strand-feeding drum 20 from any convenient source of supply, we employ, in the particular machine herein illustrated, two complementary horizontally-arranged idler-rolls 81 and 82 and a vertically-arranged idler-roll 83 all carried by the platform 25. The wire 30, in its course to the machine for being loose-coiled, first passes over the idler-roll 81, thence over the idlers 82 and 83 and into the groove 29 in the drum 20, and thence downwardly through a gap A located between the idler-rolls 32 and 35 around which the belt-like holder 31 is reversely turned, as 50 clearly shown in Fig. 6. Shortly after engaging with the drum 20, the strand 30 also engages with the inner reach of the belt-like holder 31 so as to be firmly held in the groove 29 for a distance slightly in excess of half the length 55 70 75 75

thereof, and is released from the said drum at a point in the gap A adjacent the said idler-roll 32. After being released, as described, the strand or wire 30 sags downwardly by gravity 5 in steep-pitched helical coils 34 (Figs. 1, 3, 4 and 6) around the periphery of the inner guard-member 38. As the coils reach the bottom of the strand-receiver 39, they straighten out into a horizontal plane and distribute themselves uniformly 10 in the space 41 between the inner and outer guard-members 38 and 40.

Preferably, as already pointed out, the diameter of the drum 20 is larger than the external diameter of the inner guard-member 38 15 and smaller than the internal diameter of the outer guard-member 40 to such a degree as to be equal in diameter to the mean diameter of the space 41 between the said guard-members. The guard-members 38 and 40 respectively determine 20 the inside and outside diameters of the coil being formed, and when, as above stated, the diameter of the drum 20 is equal to the mean diameter of the space 41 and hence equal to the mean diameter of the coil being formed, the wire or other strand material will uniformly 25 distribute itself within the receiver 39 without any undue piling-up at any given point and without either tightly gripping the inner guard-member 38 or looping outside of the outer guard-member 40.

When a given strand-receiver has received the desired amount of wire or the like, the same may be disconnected from the drum 20 by swinging the lever-handle 74 of the control-valve 71 into its "off" position. This movement of the valve will relieve the air pressure from under the piston 66 to thus permit the supporting-ring 56, the rotary carrier 54 and associated parts to move downwardly into the position indicated by broken lines in Fig. 1. The movement of the lever-handle 74 as just described also swings the cam 75 into a clearance position and permits the safety-plunger 77 to rise under the urge of its spring 79 so as to be entirely removed from the particular one of the sockets 80 in the carrier 54 with which it has been engaged, when the carrier is in its depressed position. The dropping of the carrier 54 also serves to disengage the inner guard-member 38 40 from the locating-flange 37 of the drum 20 and to disengage the clutch-member 44 from the clutch-member 43 so that the entire carrier 54 is free for rotation in a horizontal plane. Now by manually swinging the carrier 54, the arm 52 45 and the strand-receiver carried thereby may be swung out of line with the drum 20 and the arm 52^a may be swung into registration therewith after having been provided with a suitable strand-receiver, if desired.

When a fresh strand-receiver is aligned with the drum 20, the entire carrier 54 may be elevated to couple the strand-receiver to the said drum by swinging the hand-lever 74 of the control-valve 71 back into its "on" position, so as 50 to permit compressed air or other fluid to enter the cylinder 67 and thus raise the parts as described. This lifting of the carrier 54, however, cannot take place prior to the actual positioning of the fresh strand-receiver beneath the drum 20, owing to the fact that the control-valve 71 cannot be thrust into its "on" position until one of the sockets 80 in the carrier has been aligned with the safety-plunger 77, so that the same may be depressed thereinto.

If desired, the loose-coiling of the wire may take

place directly upon a table such as 50 without any special guard-members, though we have found that by providing inner and outer guard-members such as 38 and 40, both the internal and external diameters of the bundle of wire or the like being coiled, may be regulated within desired limits. The main factors in the success of the present invention reside in providing a rotary strand-receiver rotating around an upstanding axis and of such character as may have 10 strand material fed to it from above by suitable strand-feeding means, such, for instance, as the strand-feeding drum 20 herein shown and described. The strand-feeding drum, coaxially arranged with respect to the upstanding axis about 15 which the strand-receiver rotates, is much to be preferred, inasmuch as the strand material being coiled has imparted to it a curvature which causes it to more readily settle in loose coils, without undue spreading. Preferably, also, the rate of 20 speed at which the strand material is fed to the revolving strand-receiver corresponds as near as feasible to the mean circular speed of the coil being formed, which in the present instance lies midway between the outside of the inner guard-member 38 and the inside of the outer guard-member 40. 25

As shown in Fig. 9, the strand-receiver may have tapered inner and outer guard-members 38^a and 40^a and the strand-feeding drum may 30 be formed integrally with the inner guard-member 38, such, for instance, as at 85.

The strand-receivers 39 may be used over and over again, and if desired the wire may be shipped therein. When it is desired to ship the coils or 35 bundles of strand material to consumers in the strand-receivers, the inner guard-member 38^b of the receiver 39^b is preferably made shorter, as shown in Fig. 10, to conform to an outer guard-member 40^b so that a ring-like cover 86 may 40 be applied opposite the bottom, and the coil of wire conveniently shipped.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended 50 to be embraced therein.

We claim:

1. A machine for loose-coiling strand material, including: a strand-receiver mounted for both rotation and reciprocation about an upstanding axis and adapted to receive strand material from above; a rotary strand-feeding drum mounted substantially coaxially with respect to the said strand-receiver in position to deliver strand material thereto by gravity; means for 55 rotating the said strand-feeding drum; and axially-separable coupling means for coupling the said strand-receiver to the said drum for being rotated concurrently therewith.

2. A machine for loose-coiling strand material, including: a rotary carrier mounted for rotation in substantially a horizontal plane and for reciprocation in a substantially-vertical plane; a strand-receiver eccentrically carried by the said carrier with capacity for rotation with respect 65 thereto about an upstanding axis; a rotary strand-feeding drum mounted for rotation about an upstanding axis and positioned to deliver strand material to the said strand-receiver by gravity; and axially-separable coupling-means for cou- 70 75

pling the said strand-receiver to the said drum for being rotated concurrently therewith.

3. A machine for loose-coiling strand material, including: a strand-receiver mounted for rotation about an upstanding axis and adapted to receive strand material from above; strand-feeding means positioned above the said strand-receiver and including a rotary strand-feeding drum having a peripheral groove therein for the reception of the strand material, and pressure-means cooperating with the said strand-feeding drum and acting to press the strand material into the annular groove therein, the said pressure-means providing a gap where the groove in the strand-feeding drum is left uncovered to permit the downward helical escape of the strand material into the said strand-receiver; and means for rotating the said strand-receiver and the said strand-feeding drum simultaneously and at a definite timed relationship.

4. A machine for loose-coiling strand material, including: a strand-receiver mounted for rotation about an upstanding axis and adapted to receive strand material from above; strand-feeding means positioned above the said strand-receiver and including a rotary strand-feeding drum having a peripheral groove therein for the reception of the strand material, and an endless belt positioned to press the strand material into the groove in the said strand-feeding drum and arranged with respect to the latter to leave uncovered a portion of the groove in the said drum, to thereby permit the downward escape in a helical path of the strand material from the said groove and into the said strand-receiver; and means for rotating the said strand-receiver and the said strand-feeding drum simultaneously and at a definite timed relationship.

MICHAEL J. DEMPSEY.
